J. STRIPLING

RAIL JOINT

Filed Aug. 1, 1923

Inventor
John Stripling,
By
Briggs & Bailey
Attorneys

UNITED STATES PATENT OFFICE.

JOHN STRIPLING, OF REIDSVILLE, GEORGIA.

RAIL JOINT.

Application filed August 1, 1923. Serial No. 655,078.

To all whom it may concern:

Be it known that I, JOHN STRIPLING, a citizen of the United States, and resident of Reidsville, in the county of Tattnall and State of Georgia, have invented certain new and useful Improvements in Rail Joints, of which the following is a specification.

My invention relates to improvements in rail joints, my purpose, generally speaking, being to eliminate screw threaded or other fasteners of a like nature for securing together the meeting ends of railway rails, which fasteners have a tendency to work loose, often with disastrous results, and to provide a joint that embodies a minimum number of parts, which latter are cheap and easy to produce, strong, durable, and thoroughly reliable and efficient in use.

More particularly it is my purpose to provide a rail joint including a single locking key for a plurality of securing bolts, to provide means to facilitate the application and removal of said key with respect to such bolts, and to provide means of a very simple and effective nature for locking said key against accidental displacement from a securing status with respect to the securing bolts.

With the foregoing and other purposes in view, my invention consists in the novel features of construction, combination and arrangement of parts as will be hereinafter more fully described, illustrated in the accompanying drawings and defined in the appended claims.

In the drawings, wherein like characters of reference denote corresponding parts in the different views:—

Figure 1 is a side elevation of a rail joint embodying the novel and essential features of my invention;

Figure 2, a horizontal section through my improved rail joint;

Figure 3, a transverse section on the line 3—3 of Figure 1;

Figure 4, an enlarged detail section showing the engagement between the locking key and one of the securing bolts; and

Figure 5, a detail perspective of a portion of the locking key.

Referring now to the drawings in detail, 10 and 11 designate a pair of rails, the meeting ends of which are connected by fish-plates 12, 13 and transverse bolts 14, which latter extend through the fish-plates and the

webs of the rails in the ordinary well known manner.

The bolts 14 are headed, but instead of being screw threaded to receive clamping or securing nuts, as is usual, each of them is 60 provided, near its free end, with a transverse, dove-tailed slot 15 of limited depth that opens through one side of the bolt as shown. The inclined wall of slot 15 that is nearest to the head 16 of the bolt, for approximately one-third of its length, adjacent to the base of the slot, is cut at right angles to the axis of the bolt, as indicated at 17, for a purpose that will presently appear.

The locking key of my invention consists 70 of an elongated bar 18, headed at one end as indicated at 19 and at its other end provided with a transverse opening to receive a locking element such as a cotter pin 20 as best shown in Figure 1 of the drawings. 75 Locking key 18, in transverse section, is dove-tailed to correspond in size and shape to the dove-tailed slots 15 in bolts 14, and, as best shown in Figures 4 and 5 of the drawings, one of the inclined side faces of 80 said key is cut away or flattened adjacent to its base, as indicated at 21 to fit the corresponding right-angular cut 17 in each of the securing bolts.

At proper intervals throughout its length 85 each of the inclined side faces of locking key 18 is recessed as indicated at 22, thus providing along the key alternate dove-tailed and narrowed portions 23, 24, the latter of which are of such width as to be freely 90 insertable and removable through the narrowest portions of the slots 15 in bolts 14.

From the foregoing description considered in connection with the drawings, it is believed that the manner of using my invention 95 will be apparent. To produce a strong, durable, effective and lasting joint between the adjacent ends of rails 10 and 11, fish plates 12 and 13 are first placed, respectively, against opposite faces of the webs 100 of the rails and the bolt receiving openings therein aligned with the similar bolt receiving openings in the webs of the rails. The bolts 14 are then passed through the fish-plates and the webs of the rails, all 105 from the same side of the rails, until their heads abut one of the fish-plates and their free ends extend beyond the other fish-plate, all of said bolts being disposed with their slots 15 uppermost and relatively 110

- aligned. The locking key 18 then is engaged with the slots 15 of the bolts by aligning its recessed or narrowed portions 24 with said bolts which permits the key to drop 5 down into the slots therein as is manifest. The headed end of the key then is struck with a hammer or other instrument to slide the key longitudinally until its dove-tailed portions 23 engage the slots 15, which locks 10 the key against all but lengthwise movement out of said slots and locks the bolts 14 in securing relation to the fish plates and the ends of the rails. The head of the key engages one of the outermost bolts 14 which 15 prevents longitudinal movement of the key in one direction, while the cotter pin 20, which is passed through the opening in the other end of the key after the latter has been manipulated as just mentioned, engages 20 the other outermost bolt 14 and prevents longitudinal movement of the key in the reverse direction.
- In producing the bolts 14 the right-angular cuts 17 of the dove-tailed slots 15 are 25 spaced from the heads of the bolts a distance equal to the combined thicknesses of the fish-plates 12, 13 and the web of the rail, so that when the locking key is engaged with the bolts as aforementioned, its flattened portion 21 will contact with the outer face of the adjacent fish-plate and thus hold 30 the meeting ends of the rails firmly united. By flattening the key 18 as at 21, a relatively broad surface is presented for contact 35 with the adjacent fish-plate and sharp corners are avoided which might chip off or bite into the fish-plate and thereby affect the efficiency or ease of manipulation of the key.
- 40 It is preferable to form the locking key 18 as a single element, but if desired, it may be formed in plural sections, each having a head and an opening for the reception of a cotter pin or other securing device, it being 45 manifest, in either event, that the key or keys are readily engageable and disengageable with and from the bolts and that said key or keys as well as the bolts may be used over and over again.
- 50 It is believed from the foregoing that the construction, operation and advantages of my improvements will be fully understood. It is desired to point out, however, that changes and desirable additions may be

made in and to the structural arrangement 55 shown within the spirit and scope of my invention as defined in the appended claims.

I claim:—

1. The combination with the meeting ends of a pair of rails and fish plates engaged, 60 respectively, against opposite faces of the webs of said rails; of securing bolts extending through said fish plates and the webs of said rails, each of said bolts having a dove-tailed slot, a single locking key engageable with a plurality of said bolts to hold 65 said fish-plates in assembly with said rails, said locking key being of dove-tailed shape for engagement in the dove-tailed slots of said bolts and being recessed at intervals to provide alternate dove-tailed and narrowed portions to facilitate engagement and disengagement of the key with and from 70 said bolts, and means for locking said key against removal from said bolts. 75

2. The combination with the meeting ends of a pair of rails and fish plates engaged, 80 respectively, against opposite faces of the webs of said rails; of securing bolts extending through said fish plates and the webs of said rails, each of said bolts having a dove-tailed slot, a single locking key engageable with a plurality of said bolts to hold 85 said fish-plates in assembly with said rails, said locking key being of dove-tailed shape for engagement in the dove-tailed slots of said bolts and being adapted at one side to contact with one of said fish-plates, an inclined face of said key adjacent to the fish-plate 90 with which the key is adapted to contact being flattened throughout portions of its length to provide a flat surface for engagement with said fish plate, said key being recessed at intervals to provide alternate dove-tailed and narrowed portions to facilitate 95 engagement and disengagement of the key with and from said bolts, a head on one end of said key engageable with one of said bolts to limit longitudinal movement of the key in one direction, and an element removably engaged with the other end of the key and with another of said bolts to limit longitudinal movement of the key in an opposite direction. 100

In testimony whereof I hereunto affix my 105 signature.

JOHN STRIPLING.
